US00D794261S

(12) **United States Design Patent** (10) **Patent No.:** **US D794,261 S**
(45) **Date of Patent:** **** Aug. 8, 2017**

(54) **ELECTRONIC DOG COLLAR**

- (71) Applicant: **i4c Innovations Inc.**, Chantilly, VA (US)
- (72) Inventors: **Graham Pulliam**, Washington, DC (US); **Jeffrey Bentzler**, Playa Del Rey, CA (US); **John Michael Couse**, Toronto (CA); **Emily Hartman**, Purcellville, VA (US); **Stuart Karten**, Venice, CA (US); **Amanda Landis-Hanna**, Fairfax, VA (US); **Frederick Joel Mason**, Haymarket, VA (US); **Jeffrey Noce**, Alexandria, VA (US); **Jonathan Abarbanel**, Los Angeles, CA (US); **Joe Paul Tupin, Jr.**, Round Hill, VA (US); **Wendy L. Weinberger**, Ashburn, VA (US)
- (73) Assignee: **i4c Innovations Inc.**, Chantilly, VA (US)
- (**) Term: **15 Years**
- (21) Appl. No.: **29/564,168**
- (22) Filed: **May 11, 2016**

Related U.S. Application Data

CLAIM

The ornamental design for an electronic dog collar, as shown and described.

DESCRIPTION

FIG. 1 is a front perspective view of an electronic dog collar in accordance with our new design;
FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view thereof.

1 Claim, 5 Drawing Sheets

Related U.S. Application Data

division of application No. 29/478,136, filed on Dec. 31, 2013, now Pat. No. Des. 747,566.
